UNITED STATES PATENT OFFICE.

AMZIE N. HEMINGER, OF PLYMOUTH, INDIANA.

BICYCLE-GUARD.

SPECIFICATION forming part of Letters Patent No. 592,987, dated November 2, 1897.

Application filed April 1, 1897. Serial No. 630,314. (No model.)

To all whom it may concern:

Be it known that I, AMZIE N. HEMINGER, a citizen of the United States, residing at Plymouth, in the county of Marshall and State of Indiana, have invented certain new and useful Improvements in Bicycle-Guards; and I do hereby declare the following to be a full, clear, and exact description of the invention, such as will enable others skilled in the art to which it appertains to make and use the same.

My invention has relation to bicycles; and it consists in certain details of construction and arrangement of parts necessary to provide a housing or protection for the sprocket-wheels and sprocket-chain therefor and incidentally a protection for the bearings.

The object of my invention is to protect the parts specified from becoming soiled or injured by mud, dust, or the like, and also to provide means for protecting the garments of the rider against mutilation or from becoming soiled.

The details involved will be clearly set forth in the accompanying drawings, made a part of this application, in which—

Figure 1 is a side elevation showing my invention applied to use upon the frame of a bicycle. Fig. 2 is an elevation of the opposite side of the protector illustrated in Fig. 1. Fig. 3 is a longitudinal vertical section of the housing or protector. Fig. 4 is a detail showing a modified construction for securing the overlapping ends of the sections forming the housing. Fig. 5 is a vertical transverse section of Fig. 2 on line *a a*.

Reference to the various details involved will be had by figures, the same figure being employed to designate the same part throughout the views.

Briefly stated, my invention may be said to consist in providing a housing formed of two sections, one to receive or inclose the upper half of the sprockets and chain, while the lower section will receive and protect the lower half of said parts, and also in the provision of means to effect the locking of the two halves of the housing together in an adjusted position.

In materializing my invention I provide the members 1 and 2, forming, respectively, the upper and lower parts of the housing.

Said section 1 is of sufficient length to extend from one sprocket-wheel to the other and consists of the parallel side walls 3 and 4 and the roof-section 5, said section being extended at either end to form the end walls 6 and 7, while the lower part of the housing consists of the parallel side walls 7 and 8 and the floor-section 9, coinciding in position and extent with the upper part of the housing just referred to, the floor-section 9 being extended in a similar manner at either end to provide the end sections 10 and 11, said sections being designed to overlap the end sections 6 and 7 of the upper part of the housing. In order that said overlapping sections may be easily locked in an adjusted position, I provide that each shall have a series of corrugations 12, which will take into or interlock with each other, when the parts will be reliably held in position by the tensile property of the spring-like material forming said ends.

If deemed desirable, the interlocking of the ends may be reinforced by providing that one of the overlapping ends shall be provided with a hook 13, designed to take into one of the series of apertures 14, provided in the contiguous part of the end wall of the upper section.

In Fig. 4 I have shown a locking device of more positive character, a clip 15 being secured, preferably, to the lower part of the casting and the overlapping end wall of the other section being formed with a threaded terminal bolt 16, which will take through said clip and be held therein by a suitable nut.

In mounting the parts of the housing in their operative positions it will be observed that the horizontal section 17 of the frame will take obliquely through the housing, and in order to enable the parts to be snugly fitted together, so as to accommodate said section of the frame, I prefer to provide the angular recess 18 preferably in the lower half of the housing, said recess being formed in the walls 7 and 8 upon either side, each recess extending sufficiently near to receive the contiguous section of the part 17 of the frame.

In order to reliably anchor the housing in position, I provide the clamps 19 and 20, the former being permanently secured to the upper part of the housing upon the outer side thereof by means of the rivet 21 or otherwise.

It will be observed that said clamp is of sufficient length at one end to encircle the rear part 22 of the frame, while the lower end thereof extends into engagement with the lower part of the housing, to which it is adjustably secured by means of the slot 23 and the set-screw 24.

The clamp 20 is adjustably affixed to the upper part of the housing by means of the slot 25 and the set-screw 26, while the free end 27 is designed to take around and engage with the contiguous part of the frame, the slot 25 permitting the proper adjustment of the clamp to enable it to be readily adjusted upon any machine.

If deemed desirable, the upper and lower sections of the housing may be more securely held together by providing the adjustable clamps 28, 29, and 30, as clearly shown in Figs. 1 and 2.

It is thought that by providing that the end walls have sufficient resiliency no other means than the corrugations will be found necessary to hold the upper and lower parts in an adjusted position, as the end walls will cling into engagement with each other by means of the construction described.

The use of my invention may be stated to be as follows: The parts forming the upper and lower sections of the housing are placed upon the preferred machine in such a manner that the overlapping corrugated end walls will engage with each other, when by forcing the parts together the corrugations upon said walls will move past each other until the parts of the housing are brought sufficiently near, when the clamping strain of said walls, due to the resiliency of the metal forming the same, will reliably hold them to their work, when the free end of the outer wall having the hook 13 will be in such a position that said hook will take into one of the apertures provided therefor.

In order that the garments of the rider may be additionally protected and held entirely away from contact with the rear wheel, I provide the shield 31, secured, preferably, to the inner part of the upper half of the housing by means of the set screws or rivets 32, or otherwise. Said shield is provided with a series of perforations 33, designed to receive the interlacing of a tape or cord which coöperates with the upper portion of the frame in such a manner that a reliable guard is woven or formed by passing upward and downward, the lower ends of the loops being formed by said perforations 33.

In order that the sprocket-chain may be readily oiled without the necessity of removing the housing, I provide the oil-receiving apertures 34, formed in the roof of the housing, as clearly set forth in Fig. 3.

In order that any surplus oil falling from the sprocket-chain may be conveyed through the floor of the housing and thence to the ground, I provide the orifices 35, thus preventing the oil from draining to the forward or rear ends of the housing and there come in contact with the garments of the rider.

It will be observed that I have produced a simple, cheap, and reliably efficient means for protecting the bearings and sprocket-wheels and garments of the rider and that the parts forming the protector or housing may be readily assembled and applied to use upon any machine, and believing that the advantages, use, and construction thereof have been made fully apparent further description is deemed unnecessary.

Having thus fully described my invention, what I claim as new, and desire to secure by Letters Patent, is—

1. The herein-described attachment for bicycles consisting of the upper and lower members designed to provide a housing for the sprockets and chain therefor, the end walls of each member being extended and provided with corrugations for engagement with each other and means, substantially as described, for locking said sections in an adjusted position, as set forth.

2. The herein-described adjustable guard for bicycles consisting of the upper and lower members designed to provide a housing for the sprocket-wheels and chain therefor, each member being provided with curved end extensions having corrugations and designed to overlap and engage each other; a hook formed upon the end of one of said corrugated extensions and apertures designed to receive said hook formed in a contiguous part of the opposite extension; a perforated plate secured to the upper member, and means substantially as described, for anchoring said members in their operative position upon the bicycle-frame, substantially as specified and for the purpose set forth.

In testimony whereof I affix my signature in presence of two witnesses.

AMZIE N. HEMINGER.
